UNITED STATES PATENT OFFICE.

GEORGE BELL, OF PRESTON, AND JOHN BOARDMAN, OF ASHTON, PRESTON, ENGLAND.

KNITTING MACHINE.

Application filed April 13, 1927, Serial No. 183,410, and in Great Britain March 5, 1926.

This invention relates to knitting machines in which a selector is provided for grouping, separating, or selecting the needles or their equivalents in predetermined formations and repeating such grouping of the needles as the selector travels across the needle bed.

According to this invention the selector comprises a slide adapted to be moved along the needle bed and carrying an arrangement of fixed and movable cams which operate in conjunction with a switch cam which is moved from one position to another by the needle butts to cause certain of the needles to occupy an upper position and others a lower position in a predetermined order which is determined by the setting of the first group of needles.

In order that the said invention may be clearly understood and readily carried into effect, the same is described more fully with reference to the accompanying drawings, in which:—

Fig. 1 is a plan of a selector constructed in accordance with this invention.

Fig. 2 is an end elevation of the selector looking in the direction of the arrow shown in Fig. 1.

Fig. 3 is a front view of the bottom edge of the selector.

Fig. 4 is an inverted plan of the selector showing the cams.

Fig. 5 is a view of the selector looking in the direction of the arrow indicated in Fig. 4, and

Fig. 6 is a similar view to Fig. 4 showing a modified construction of switch cam.

A indicates a slide, B, C, the two stationary cams, D, E, two movable cams, and F the switch cam.

The slide A is formed or provided with a key portion a adapted to travel along an existing guide slot which extends the whole length of the needle bed. The slide A may be attached to the existing cam box or it may be formed as one unit in a piece therewith. The cam B is formed with an inclined surface b and a recessed portion b^1 along which the butts of the needles which have been pushed up travel. The cam C is formed with two inclined surfaces c , c^1 . The cams D and E are formed with inclined surfaces d , d^1 and e , e^1 . These cams are mounted on spindles d^2 , e^2 which are free to swivel in bearings in the slide against the action of springs d^3 , e^3 which normally

maintain the cams in the position shown in Fig. 4. The switch cam F is mounted on a spindle f which is free to turn in a bearing in the slide and is maintained in one or other of its two positions by a spring pressed finger f^1 having a V shaped end f^2 that bears against a rod f^x which projects through an aperture in the slide. When the selector is travelling in one direction the needle butts are guided by the inclined surfaces b , d , through the channel G and along one edge or the other, say for example, the upper edge, of the switch cam F until a shoulder f^4 on such cam comes in contact with the first butt which then turns the switch cam to the position indicated by the dotted lines, in which position the butts that were formerly trapped by the shoulder f^4 pass out through the space that is formed at H, and cause their needles to occupy an upper position in the needle bed. With the switch lever F in the altered position the needle butts that are now guided through the passage G are deflected down the under edge of the switch cam F until a shoulder f^5 thereon strikes the foremost butt which then restores the switch lever to the position indicated by the full lines and leaves a passage through which the needle butts can pass and cause their needles to occupy a lower position in the needle bed, these operations being repeated until the slide comes to rest at the end of the needle bed. As each batch of needles is separated by the selector cams they are acted upon by the cams in the cam box which follow immediately after to actuate the needles to perform the knitting operation. When this has taken place all the needle butts are left in line along the needle bed at a level in which they will be engaged by the inclined surface e^1 of the cam E on the return movement of the slide with the result that the cam will be turned against the action of the spring e^3 to allow the butts to pass to the inclined surface d^1 of the cam D, which will then be tilted in like manner and allow the butts to pass through the passage G. The portion f^3 of the switch lever F may be made of sufficient length to accommodate any predetermined number of butts and supposing for example that it is made a correct length for actuating nine needles, then if the first nine needles be arranged in such a manner that some are on top edge of the tongue and some on the lower, when the selector moves

across the needle bed the tongue must necessarily arrange all the needles in the bed in sequence in the order of the first nine, except that those thrown up in the first group are 5 thrown down in the second. The method of obtaining these results is as follows:—The first nine needles are pushed up or left down by hand or mechanical means in the order desired, for example two up, six down, one 10 up. The tongue f^3 is moved into the position of the tip F pointing upward. When the selector moves over the needles, those which are pushed up will pass over the higher edge b^2 of the cam B and by way of 15 the recessed portion b^1 on to the top edge of the tongue f^3 . Those needles which are left down will pass through the passage G to the lower edge of the tongue f^3 which then continues to arrange needles in similar 20 order across the whole width of the machine with the exception that each batch of needles will be arranged alternately, that is to say, if the first batch contains two up, six down and one up, the next batch will contain 25 two down, six up, and one down and the next batch two up, six down and one up and so on. If it is desired to keep the first selection in exactly the same order across the whole width of the machine the switch 30 cam is made in two parts F F¹, as seen in Fig. 6, which are respectively pivoted at f^6 and intergeared at f^8 by one or more teeth and of any desired ratio so that one part in motion actuates the other part and automatically reverses the order of the needles 35 arranged by the plain one piece tongue above described, thus the order of needles thrown up in this case is the same in every group and not reversed as is the case when 40 a one piece switch cam is employed. A stationary cam E¹ is also substituted for the pivoted cam E. In this modification supposing the needles are to occupy a position one up and eight down in each successive 45 group, the tongue is in its upper position with the upper needle on its top side. When this needle passes between a shoulder f^9 on the part F¹ and a cam surface c^1 on the cam C, it reverses the position of the parts F F¹.

and holds them in that position whilst the 50 attachment moves over the needle bed for the space of one needle with the result that the part F will deflect the next needle on to its top side and immediately the previous upper needle passes between the shoulder f^9 and cam surface c^1 a spring will return the parts F F¹ to their normal position with the 55 result that the next eight needles will pass underneath the parts F F¹. On the return 60 passage of the attachment the needles pass between the shoulder f^{10} on the part F¹ and the stationary cam E¹. This arrangement will automatically give any selection with the exception of a full selection that is to say 65 nine needles up and nine needles down and this can be automatically obtained by the single piece switch lever F. In applying the selector or selectors to a circular knitting machine it may be built in or form an attachment thereto and only one setting of 70 the needles would be required for any one pattern. For knitting fabrics with stripe or check patterns no setting of the needles is required, the selector being fully automatic. 75

What we claim as our invention and desire to secure by Letters Patent in the United States is:—

1. A selector for knitting machine needles comprising a switch cam mounted for movement to reverse positions for moving the needles to either of two positions, and means operable by the needles in both of said positions of the needles to move the switch cam to the reverse positions. 80

2. A selector for knitting machine needles comprising a switch cam pivotally mounted to swing to reverse positions for moving the needles to either of two positions, and means operable by contact with the needles in both of said positions thereof for swinging the switch cam from either position to the other position. 85 90

In witness whereof we have signed this specification.

GEORGE BELL.
JOHN BOARDMAN.
